(57) **CLAIM**

The ornamental design for a fence post hinge bracket as shown and described.

DESCRIPTION

FIG. 1 is a perspective view of the fence post hinge bracket, shown with environment;

FIG. 2 is a perspective view of the fence post hinge bracket;

FIG. 3 is a top plan view of the fence post hinge bracket;

FIG. 4 is a front elevational view of the fence post hinge bracket of FIG. 3;

FIG. 5 is a right side elevational view of the fence post hinge bracket of FIG. 3, in which the left side elevational view is a mirror image of the right side elevational view shown; and, FIG. 6 is a rear elevational view of the fence post hinge bracket of FIG. 3.

The broken line showing of an inner fence post and adapters is included for the purpose of illustrating environmental structure and forms no part of the claimed design.
